UNITED STATES PATENT OFFICE.

LOUIS BERGEN, OF NEW YORK, N. Y.

APPARATUS FOR DISPENSING AND DRAWING LIQUIDS.

SPECIFICATION forming part of Letters Patent No. 297,221, dated April 22, 1884.

Application filed June 12, 1883. (No model.)

To all whom it may concern:

Be it known that I, LOUIS BERGEN, of New York, in the county and State of New York, have invented a certain new and useful Improvement in Apparatus for Drawing and Dispensing Liquids, of which the following is a specification.

This improvement relates to draft or dispensing apparatus for effervescent or foaming liquids.

The improvement consists in the combination, in such an apparatus, of two vessels or compartments, pipes leading to the two vessels or compartments from a receptacle containing the liquid, a pipe or passage establishing communication between the two vessels or compartments, a valve controlling the pipe or passage just named, and vents or gas-escapes in the upper part of the two vessels or compartments whereby liquid may be introduced into either of the vessels or compartments, communication may be opened between this vessel or compartment and the other vessel or compartment to relieve such liquid of surplus gas, and subsequently the gas may be allowed to escape from the vessel or compartment into which it was admitted.

The accompanying drawing represents a central vertical section of an apparatus embodying my improvement.

A' A² designate two vessels, which may be of cylindrical form and made of enameled cast-iron. They have covers a' a², which may be made of the same material, and are shown as secured in place by means of bolts b, hinged to the exterior of the vessels, and adapted to fit in slots in the edges of the covers, in conjunction with nuts applied above the covers.

B designates a pipe leading from a barrel or other receptacle containing the liquid to be dispensed, and B' B² designate branch pipes extending from the pipe B to the bottoms of the vessels A' A². These pipes B' B² may be coupled or united in any suitable manner, and the pipes B' B² may be connected by couplings to nipples extending from the vessels A' A². They are provided at some distance below the vessels with cocks B³ B⁴.

D' D² designate pipes coupled or otherwise united to the pipes B' B² between the cocks

B³ B⁴ and the vessels A' A². These pipes D' D² extend outside the vessels A' A² to a point considerably above the bottoms thereof. They are provided near the ends with cocks or faucets D³ D⁴.

55

C designates a pipe extending between the vessels A' A², and connected thereto by couplings or otherwise. This pipe is provided with a cock, C. All the pipes may be tin-lined lead pipes, or they may be of any other 60 suitable material.

E' E² are vents or gas-escapes arranged on the tops of the vessels A' A² and consisting of suitable cocks. Obviously, a single vessel having two compartments could be used in 65 lieu of the two vessels and a passage extending between such compartments might be used in lieu of the pipe C, a suitable valve being provided to control such passage. When the apparatus is out of use, all its cocks are closed. 70

To use the apparatus, one of the cocks B³ or B⁴ is opened—for instance, the cock B³. Then the liquid rises by its pressure, or is raised by a pump into the vessel A'. It fills the vessel as far as it can, the height to which it rises 75 in the vessel being dependent on the pressure of the liquid when it enters the vessel. The cock B³ is then closed, and the cock C is opened to allow the surplus gas to pass from the vessel A', into the vessel A². The cocks of the 80 vents or gas-escapes E' E² may now be opened so as to allow the gas to escape from the vessel A² and to prevent the forming of a vacuum in the vessel A', when the cock D³ of the pipe D' is opened. The cocks C' and E² may 85 be closed as soon as the cock E' is opened. After the cock D³ is opened the liquid will flow from the vessel A' through the said pipe D' into any vessel which may be properly placed to receive it. Owing to the height to 90 which the pipes D' D² extend above the bottom of the vessels, a quantity of liquid will remain in the vessel. After the desired amount of liquid is drawn from the vessel the cock D³ of the pipe D' and the vent-cock E' 95 are closed. As soon as the cocks C' and E² are closed the cock B⁴ of the pipe B² may be opened to allow liquid to enter the vessel A², and immediately after the cocks D³ and E' are closed the cock B⁴ may be closed to cut off 100

the supply of liquid, and the cock C' may be opened to permit surplus gas to escape from the vessel A² into the vessel A'. After this the cocks C' and E' may be closed and the cocks E² and D⁴ opened to permit the liquid to escape from the vessel A². A quantity of liquid will remain in the vessel A² because of the height to which the pipe D² extends above its bottom. It will thus be seen that both vessels may be used at the same time, as liquid can be raised into either while liquid is being discharged from the other. This feature is important, as it enables liquid to be drawn with greater rapidity from the apparatus than otherwise it could be drawn from the same. Where the liquid to be drawn or dispensed is very highly charged with gas, the surplus gas may be allowed to escape from one vessel containing it by opening the cock C'; then the cock C' may be closed and the vent of the vessel which received the gas may be opened to permit the escape of the gas, and this operation may be repeated several times before the liquid is allowed to escape from the vessel containing it.

This apparatus is admirably adapted for

drawing or dispensing ales and other malt liquors.

What I claim as my invention, and desire to secure by Letters Patent, is—

1. In an apparatus for drawing or dispensing liquids, the combination of two vessels or compartments, pipes leading to the vessels or compartments from a receptacle containing the liquid, a pipe or passage establishing communication between the two vessels or compartments, and provided with a valve or cock, and vents or gas-escapes in the upper part of the vessels or compartments, substantially as specified.

2. In an apparatus for drawing or dispensing liquids, the combination of the vessels A' A², pipes B' B², provided with cocks B³ B⁴, the pipe C, provided with the cock C', the pipes D' D², provided with cocks or faucets D³ D⁴, and the vents or gas-escapes E' E², substantially as specified.

LOUIS BERGEN.
